UNITED STATES PATENT OFFICE

2,135,789

FUSE

Theodore Birkenmaier, St. Louis, Mo., assignor
to W. N. Matthews Corporation, St. Louis, Mo.,
a corporation of Missouri

Application April 7, 1938, Serial No. 200,590

23 Claims. (Cl. 200—114)

This invention relates to fuses, and with regard to certain more specific features, to expulsion fuses.

This invention is an improvement upon the construction disclosed in my United States Patent 2,077,207, dated April 13, 1937.

Among the several objects of the invention may be noted the provision of means for obtaining the objects set forth in the above-named patent but by use of the knife type of contacts, rather than by the cantilever spring type of contacts of the patent; the provision of apparatus of the class described which eliminates the necessity for any terminal-engaging element being movable on the door; and the provision of a switch of the class described which is even more reliable than the switch of the patent. Other objects will be in part obvious and in part pointed out hereinafter.

20 The invention accordingly comprises the elements and combinations of elements, features of construction, and arrangements of parts which will be exemplified in the structures hereinafter described, and the scope of the application of 25 which will be indicated in the following claims.

In the accompanying drawings, in which is illustrated one of the various possible embodiments of the invention—

Fig. 1 is a vertical section showing the invention fused and in circuit-closing position;

Fig. 2 is a view similar to Fig. 1, but showing a first movement as a disconnection occurs;

Fig. 3 is a view similar to Fig. 2 showing a final position of parts after disconnection;

35 Fig. 4 is an inside view of the door with the fuse parts thereon in the position such as shown in Fig. 1;

Fig. 5 is a horizontal section taken on line 5—5 of Fig. 1;

40 Fig. 6 is a horizontal section taken on line 6—6 of Fig. 1; and,

Fig. 7 is a horizontal section taken on line 7—7 of Fig. 4.

Similar reference characters indicate corresponding parts throughout the several views of the drawings.

In my Patent 2,077,207, I show an expulsion fuse construction in which the fuse link, after melting, and after being expelled from a fuse tube, hangs from the fuse unit in an unelectrified condition, with a wide separation of the link separated ends. While the apparatus of that patent is effective, it is desirable, under certain circumstances, to employ a so-called knife contact 55 means. For example, where a low-temperature

rise is desired, such knife contacts are desirable. Such knife contacts, in the case of the patent would present too much friction to downward movement of the lower movable terminal-engaging element of the patent. By means of the present invention, instead of increasing the forces necessary to make the device of the patent operate with knife contacts, I eliminate the required movement of the lower terminal-engaging element.

It is furthermore true that in general a pair of relatively fixed terminal-engaging elements for engagement with a pair of fixed line terminals is preferable, because of its simplicity, to a construction wherein one or more of these terminals or elements is movable with respect to the other in response to circuit-breaking action.

Referring now more particularly to Fig. 1, there is shown at numeral 1 a box made of insulating material such as porcelain adapted to be supported by means of bolts 3 and having anchored therein conducting line terminals 5. The line terminals include wire clamps 7 for respective wires 8 (Fig. 6) and riveted U-shaped spring conducting members forming so-called knife contacts 9.

The box 1 is open at the bottom as indicated at 11, and has a front opening 13 covered by a door 15 hinged on a pin 17. The hook-shaped portion 19 on the door which effects hinging is open as shown at 21 so that the door may be removed from the box after it has been pulled to an open position. A ring 23 is provided for pulling the door open. The door 15 is also made of insulating material, such as Bakelite, for example.

35 The door 15 has attached thereto, by means of screws 25, upper and lower terminal-engaging elements 27 and 29 respectively. These terminal-engaging elements 27 and 29 are made of conducting material and are hollow and have 40 flat sides 31 and 33 for engagement with the flat sides of the U-shaped spring conducting blades or clips 9.

The spring pressure between the clips 9 and the terminal-engaging elements 27 and 29 is relatively high, so that a good contact is obtained without undue temperature rise in the switch under operating conditions. This also induces friction which maintains the door 15 in closed condition but which permits of pulling the door 50 open, when desired.

The hollow portion of the upper terminal-engaging element 27 is open at the top and bottom, and at the top is threaded to receive a threaded enclosing cap 35. The cap also functions as a 55

clamp for the upper headed-end 37 of a fuse link 39. The fuse link 39 has a reduced portion 41 adapted to melt upon overload and to open the circuit. Its lower end is composed of flexible conducting wire, as indicated at 43.

The fuse link 39, 43 passes through an insulating tube 45 which is rigidly supported at its upper end by the upper terminal-engaging element 27. This tube 45 passes downwardly in spaced relation to and through the hollow lower terminal-engaging element 29. It is also supported in an extension 28 from the door 15. The lower end of the tube 45 is open, as indicated at 47, and has an open notch 49 at one side. A septum 52 associated with the box forms a saddle around the tube 45, and with the adjacent support 28 divides the box roughly into an upper and lower compartment, to tend to prevent current leakage between the line terminals 5.

Slidably arranged on the insulating tube 45 is a second insulating tube or sleeve 51 which is also slidable through the hollow lower terminal-engaging element 29. It is prevented from turning in the hollow cylindrical form of the element 29 by means of a groove 53 therein, with which cooperates a pin 55 in the terminal-engaging element. This pin 55, when contacted by the upper end of the groove 53, also limits the downward movement of the sleeve or tube 51, as indicated in Fig. 3.

The lower end of the sleeve 51 is provided with a fixed collar 57 which may or may not be made of conducting material, although in the present embodiment it is so shown. This collar is formed on one side with a smooth, rounded, anti-friction saddle 59. The notch 49 in fixed tube 45 cooperates with the inner edge of the saddle 59 as shown in Fig. 1 to prevent interference between the lower end of the tube 45 and the fuse link.

The top of the collar 57 forms a seat for a spring 61. Above the spring 61 and slidably arranged upon the outside of the sleeve 51 is a conducting sleeve or contact 63. This sleeve or contact carries a pin 65 which slides in said groove 53, so that sliding of contact 63 is permitted, but rotation is prevented. If the sleeve 51 be pushed upwardly, the conducting sleeve encounters the lower terminal-engaging element 29 to make a good contact. Further upward movement of the sleeve 51 results in a fixed shoulder 57 thereon compressing the spring 61, so that the contact 63 is tightly biased and held against the stationary terminal-engaging element 29.

The outside of the pin 65 forms a threaded post 66 for reception of a thumb-nut 68 and washer 70 for clamping the looped end portion of the fuse 43.

Operation of the device is as follows, assuming that the door 15 has been removed, and that a new fuse is required:

The cap 35 is removed and any old upper fuse element removed. The same is true of such lower fuse element as may be under the nut 68 and washer 70.

The new fuse is fed (flexible part first) through the upper terminal-engaging element 27 and its head 37 is clamped in position by the enclosing cap 35. The lower end of the fuse then extends from the opening 47 and from the lower open end 67 of the ring 57. It is threaded around the saddle 59 and then pulled upwardly until the conducting contact 63 is pushed up against the terminal-engaging element 29. The pulling is then continued until compression is placed in the

spring 61, thus forcing the contact 63 and element 29 together. The flexible end of the fuse link is then wrapped around the post 68 and nut 68 tightened down.

From Fig. 4 it will be seen that the lower end of the groove 53 is normally not far from the pin 55, so that there is a limit to which the spring 61 may be compressed by pulling up on the saddle 59 with the portion 43 of the fuse link.

From the above, it will be seen that the spring 61 in tending to expand reacts to push down the saddle 59 to place tension in the fuse, but at the same time it holds the sliding contact 63 against the lower terminal-engaging element 29. If, then, the door 15 has its hook 19 applied to the pin 17 and is rotated into the position shown in Fig. 1, the terminal-engaging elements 27 and 29 will engage the line terminals 9 in knife fashion and the door will be held shut while the circuit is closed through the fuse (Fig. 1).

Upon overload, the reduced portion 41 melts and the fuse is at first drawn down by the pull at the saddle 59 caused by the expansion of the now released spring 61 (see Fig. 2). If, as often occurs under conditions of heavy overload or short circuit, there is an explosive action, the effect is to blow the entire link 43 from the tube 45, and finally the condition of Fig. 3 is reached wherein gravity causes the assembly of the contact 63, spring 61, ring 57 and sleeve 51 to continue downwardly until limited by the action of the pin 55 at the upper end of the groove 53, the flexible part of the link in the meanwhile having been drawn out over the smooth saddle 59 as indicated in Fig. 2. Finally, the link falls entirely out of the tube.

Upon small or so-called dragging overloads, even a relatively flexible portion such as 43 may remain in the tube 45 after expansion of the spring 61, but it has a greater separation than shown in Fig. 2, because of the substantial drop which occurs in the tube 51 in moving from the position shown in Fig. 2 to that shown in Fig. 3. Thus, although flexibility is desirable in the portion 43, it will be seen that it is not absolutely necessary, and that various degrees of flexibility will be suitable. Furthermore, the invention is even useful with relatively stiff fuse links, because in such cases, although the bent link cannot slide over the saddle 59, nevertheless, when it separates, the upward reaction of the spring 61 on contact 63 accelerates the tube 51 downwardly and gravity further aids the downward motion, until a relatively wide separation of the ends of the fuse link is effected.

The ultimate result is that the lower fragment of the fuse link which is left may hang from the box, but is electrically dead, because the contact 63 has separated under the gravity action from the lower terminal-engaging element 29. It will be seen that the action is independent of any motion of the lower line terminal or of the terminal-engaging element 29, and thus distinguishes from the construction shown in said Patent 2,077,207.

Another distinction is in the provision of the saddle 59 and the notch 49 adjacent the saddle 59. The notch 49 permits the lower flexible portion 43 of the fuse link to reach the smooth, hard surface of the saddle 59 without contacting the side of the opening 47 of the inner tube 45. Thus, the retarding action of friction (the saddle 59 being of the nature of an anti-friction device) is reduced. It will be understood that, if desired,

the saddle 59 may be replaced by an equivalent wheel, roller or the like.

Another feature distinguishing the invention from that shown in said Patent 2,077,207 is that the contact 4 between the lower terminal-engaging element 29 and the lower line terminal 9 is independent of the spring which provides the tension in the fuse link. Thus the problems of proper electrical contact pressure may be solved independently of the problem of operating pressures required for proper automatic operation.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In apparatus of the class described, a pair of relatively fixed terminal-engaging elements, a contact movable with respect to one of said terminal-engaging elements, a fuse link fastened to the contact, said fuse link passing to a connection with one engaging element, means pressing the fuse link between its ends, and expansive means between said contact and said pressing means adapted both to force said pressing means to tension said link and to force said contact against the other terminal-engaging element.

2. In apparatus of the class described, spaced line terminals, a fused support, a pair of fixed terminal-engaging elements on said support and cooperating respectively with said line terminals, a contact movable with respect to one of said terminal-engaging elements, a fuse fastening means on the contact, a fuse link passing from a connection with one engaging element to a connection with said contact, means touching the fuse link between its ends, and expansive means between said contact and said touching means adapted both to tension said link and to force said contact against the other of said terminal-engaging elements.

3. In apparatus of the class described, spaced line terminals, a fuse support, a terminal-engaging element fixed on said support and cooperating with one line terminal, another terminal-engaging element fixed on the support and a contact movable with respect thereto, a fuse fastening means on the contact, a fuse link passing from the first engaging element through said second engaging element and through and to the contact, the contact being movable and held in engagement with the second-named engaging element by the unfused link, and being separable therefrom by gravity when the link fuses.

4. In apparatus of the class described, spaced line terminals, a fuse support, a terminal-engaging element fixed on said support and cooperating with one line terminal, another terminal-engaging element fixed on the support and a contact movable with respect thereto, a fuse fastening means on the contact, a fuse link passing from the first engaging element and to the contact, the contact being movable and held by the unfused link in engagement with the second-named engaging element, and being separable by gravity when the link fuses, and means reacting between said contact and the link to tension the latter.

5. In apparatus of the class described, spaced

line terminals, a fuse support, a terminal-engaging element fixed on said support and cooperating with one line terminal, another terminal-engaging element fixed on the support and a contact movable with respect thereto, a fuse fastening means on the contact, a fuse link passing from the first engaging element and to the contact, the contact being movable and held by the unfused link in engagement with the second-named engaging element, and being separable by gravity when the link fuses, and spring means reacting between said contact and the link to tension the latter, said spring means being adapted to be tensioned by shortening of the fuse when the latter is attached to the contact.

6. A fuse comprising a fuse holder, a terminal-engaging element at one end of said holder, said holder being open at the other end, a slideable member on said holder, said slideable member having an open end normally adjacent the open end of the holder, a fuse contact slideable on said member, a fuse joining said last-named contact and said terminal-engaging element, and resilient means reacting between the member and said contact thereon.

7. A fuse comprising a fuse tube, a terminal-engaging element at one end of said tube, said tube being open at the other end, a second slideable tube on said first tube, said second tube having an open end normally adjacent the open end of the first tube, a fuse contact slideable on said second tube, a fuse joining said last-named contact and said terminal-engaging element, resilient means reacting between points at the end of said slideable tube and said contact thereon, and a second terminal-engaging element adapted to be contacted by the contact upon movement of the slideable tube toward the first-named terminal-engaging element by shortening of the link.

8. In a fuse, a fixed fuse tube, a terminal at one end of said tube, said tube being open at the other end, a slideable tube on said first tube adjacent the open end, said slideable tube having an open end normally adjacent the open end of the first tube, a second terminal, a contact slideable on the slideable tube and lying outside the reach between the two terminal elements, a fuse fastened to the terminal element and extending through the fixed tube and of a length to hold the slideable tube in a position to force the contact against the second terminal element, and resilient means reacting between the contact and a portion associated with the slideable tube.

9. In a fuse, a fixed fuse tube, a terminal at one end of said tube, said tube being open at the other end, a slideable tube on said first tube adjacent the open end, said slideable tube having an open end normally adjacent the open end of the first tube, a second terminal, a contact slideable on the slideable tube and lying outside the reach between the two terminal elements, a fuse fastened to the terminal element and extending through the fixed tube and of a length to hold the slideable tube in a position to force the contact against the second terminal element, and resilient means reacting between the contact and a portion associated with the slideable tube, said terminals being relatively fixed.

10. A fuse comprising an insulating tube, a fixed terminal-engaging element enclosing one end of said tube, a second fixed terminal-engaging element, a telescoping and insulating tube associated with the insulating tube, and a contact slideable on said telescoping tube and engage-

- able with the second-named fixed terminal-engaging element.
11. A fuse comprising an insulating tube, a terminal-engaging element near one end of said tube, a second terminal-engaging element near the other end of the tube, a telescoping and insulating tube associated with the insulating tube, a contact slidable on said telescoping tube and engageable with the second-named terminal-engaging element, and resilient means adapted to react between the slidable contact and the telescoping tube.
12. A fuse comprising an insulating tube, a terminal-engaging element near one end of said tube, a second terminal-engaging element near the other end of the tube, a telescoping and insulating tube associated with the insulating tube, a contact slidable on said telescoping tube and engageable with the second-named terminal-engaging element, resilient means adapted to react between the slidable contact and the telescoping tube, and a link joining the contact and first-named terminal-engaging element, said link being of a length to tension said resilient means to react.
13. A fuse comprising an insulating tube, a fixed terminal-engaging element enclosing one end of said tube, a second fixed terminal-engaging element near the other end of the tube, a telescoping and insulating tube associated with the fixed insulating tube, a contact slidable on said telescoping tube and engageable with the second-named fixed terminal-engaging element, a fuse link joining the first-named terminal-engaging element and said contact, anti-friction means at the end of said slidable tube adapted to be contacted by the link, and resilient means reacting from the end of said tube and said contact.
14. A fuse comprising a fuse holder, a terminal-engaging element on said holder, a second terminal-engaging element, an insulating sliding member associated with the holder, and a contact slidable on said sliding member and engageable with the second terminal-engaging element.
15. A fuse comprising a fuse holder, a terminal-engaging element on said holder, a second terminal-engaging element, an insulating sliding member associated with the holder, a contact slidable on said sliding member engageable with the second terminal-engaging element, and resilient means reacting between the sliding member and the contact.
16. A fuse comprising a fuse holder, a terminal-engaging element on said holder, a second terminal-engaging element, an insulating sliding member associated with the holder, a contact slidable on said sliding member engageable with the second terminal-engaging element, resilient means reacting between the sliding member and the contact, and a fuse link joining the first-named terminal-engaging element and the contact and forcing the sliding member to push the contact against the second terminal-engaging element and to tension said resilient means.
17. In a fuse, a fixed fuse tube, a fixed terminal element at one end of said tube, said tube being open at the other end, a second slidable tube on said first tube adjacent the open end, said second tube having an open end normally adjacent the open end of the first tube, a second fixed terminal element, a movable contact on the slidable tube lying outside the reach between the two terminal elements, and a fuse adapted to be fastened by the first-named terminal element and to extend through the fixed tube and to hold the slidable tube to force the contact against the second terminal element, and means for tensioning said contact against the second terminal element and for tensioning the fuse.
18. In apparatus of the class described, a box, a door on said box, upper and lower line terminals in said box, fixed terminal-engaging elements on said door for contacting said line terminals, an insulating tube extending from said upper terminal-engaging element downwardly past the lower line terminal, a second insulated tube telescoping the first tube, a resilient contact on said second tube adapted to fasten a fuse link, and a link joining said last-named contact and the upper terminal-engaging element.
19. In apparatus of the class described, a box, a door on said box, upper and lower line terminals in said box, a terminal-engaging element on said door for said upper line terminal, an insulating tube extending from said upper terminal-engaging element downwardly past the lower line terminal, a second insulated tube telescoping the first tube, a contact on said second tube adapted to fasten a fuse link, a link joining said last-named contact and the terminal-engaging element, and a lower fixed terminal-engaging element on said door and adapted to be engaged by said contact when the contact is moved toward the upper terminal-engaging element, said link in normal position holding said contact against the lower terminal-engaging element.
20. In apparatus of the class described, a box, a door on said box, upper and lower line terminals in said box, fixed terminal-engaging elements on said door for said line terminals, an insulating tube extending from the upper terminal-engaging element downwardly past the lower line terminal, a second insulating tube telescoping the first tube, a movable contact on said second tube adapted to fasten a fuse link, a link joining said last-named contact and the upper terminal-engaging element, the lower one of the terminal-engaging elements on said door being adapted to be engaged by said contact when the contact is biased toward the upper terminal-engaging element, said link in normal position holding said contact so biased, and resilient means reacting between the contact and a portion associated with the link.
21. In apparatus of the class described, a box, a door on said box, upper and lower line terminals in said box, an upper terminal-engaging element on said door for said upper line terminals, an insulating tube extending from said upper terminal-engaging element downwardly past the lower line terminal, a second insulated tube telescoping the first tube, a contact on said second tube adapted to fasten a fuse link, a link joining said last-named contact and the first-named terminal-engaging element, and a lower terminal-engaging element fixed on said door and adapted to be engaged by said contact when the contact is moved toward the upper terminal-engaging element, and means reacting between said contact and a portion of the fuse link to tension said link and to force said contact against the lower terminal-engaging element.
22. A fuse comprising a fuse holder, a terminal-engaging element at one end of said holder, said holder being open at the other end, a slidable member on said holder, said slidabile member having an open end normally adjacent the open end of the holder, a fuse contact slid-

able on said member, a fuse joining said last-named contact and said terminal-engaging element, resilient means reacting between the member and said contact thereon, a second terminal-engaging element with respect to which said slidable member moves, and means between the second terminal-engaging element and the slidable member limiting downward movement of the latter.

10 23. A fuse comprising a fuse holder, a terminal-engaging element at one end of said holder, said holder being open at the other end, a slidable member on said holder, said slidable member having an open end normally adjacent

the open end of the holder, a fuse contact slideable on said member, a fuse joining said last-named contact and said terminal-engaging element, resilient means reacting between the member and said contact thereon, a second terminal-engaging element with respect to which said slidable member moves, means between the second terminal-engaging element and the slidable member limiting downward movement of the latter, and means between said fuse contact and 10 said slidable member limiting the relative motion between the two in order to limit the compression that may be placed in said resilient means.

THEODORE BIRKENMAIER.
